Attorney

UNITED STATES PATENT OFFICE.

EMANUEL JACOBS, OF DETROIT, MICHIGAN.

RAZOR-HONING DEVICE.

Application filed August 9, 1923. Serial No. 656,581.

This invention relates to a razor honing device, and has special reference to that class of devices adapted to be held in one hand while the razor blade is manipulated in the device by the other hand.

My invention aims to provide such a device wherein opposed stones or sharpening instrumentalities form a guide for a razor blade that may be oscillated to first engage 10 one stone and then another as the blade is moved back and forth in the device; the relation of the stones or sharpening instrumentalities being such as to insure a proper angle to the blade when shifted against the 15 stones.

My invention further aims to provide a novel mounting for razor honing instrumentalities by which such instrumentalities can be easily removed and renewed or different 20 kinds of honing instrumentalities substituted therefor. The mounting is extremely simple in construction, easy to hold and of such size, with the honing stones therein, that it may conveniently form part of a 25 shaving kit.

My invention will be hereinafter described and then claimed, and reference will now be had to the drawing wherein—

Fig. 1 is a perspective view of the device;

Fig. 2 is a front elevation of the same, partly broken away and partly in section;

Fig. 3 is a side elevation of the device shown in Figs. 1 and 2;

Fig. 4 is a perspective view of one of the stone holders;

Fig. 5 is a perspective view of a coupling member;

Fig. 6 is a perspective view of a filler member, and

Fig. 7 is an enlarged horizontal sectional view taken on the line XIII—XIII of Fig. 3.

The device comprises opposed channel holders 14 for stones 15, and the inner end 45 of each holder has wings 16 adapted to be engaged by channel shaped coupling members 17 which retain a plurality of shims or filler members 18 between the wings 16 of the holders. In this instance the stones 15

correspond in length to the holders 14 with 50 the shims 18 maintaining the holders spaced apart and the lower ends of the stones in the holders. Should the coupling members 17 become loose on the wings 16, additional shims, made of paper, cardboard or any suitable 55 material, may be placed between the wings of the holders. The coupling members 17 will serve as finger pieces and facilitate a hand holding the lower end of the device while a razor blade is manipulated 60 between the stones 15. The holders 14 may have a cross sectional configuration which will cause opposed walls of each holder to serve as clamping members for the stone placed in the holders, and it is obvious that 65 the stones may be removed, reversed or renewed.

With the holders firmly clamped together and held in the left hand, a razor blade may be manipulated by the right hand, by first 70 placing one side wall of the blade in engagement with one of the stones and then in engagement with the other stone the edge of the blade can be sharpened and honed by drawing the blade in one direction or moving it back and forth against the stones of the honing device. There is no danger of the razor blade cutting either of the hands when properly manipulated and no danger of the blade being placed at too acute angle relative to either stone when sharpening or honing the blade.

What I claim is:

A sharpening device wherein a blade is adapted to be moved at substantially a right 85 angle to the longitudinal axis of said device, said device comprising opposed channel shaped holders having outturned extensions at one end forming wings, stones in said holders, filler pieces interposed between 90 the wings of one holder and the wings of the other holder and extending between said stones to space said holders apart, and U-shaped finger pieces clamping the filler pieces between the holder wings by engaging outer 95 walls of said holder wings.

In testimony whereof I affix my signature.

EMANUEL JACOBS.
